UNITED STATES PATENT OFFICE.

CHARLES ALBERT YALE, OF BURLINGTON, VERMONT, ASSIGNOR TO YALE WONDER CLOCK COMPANY, OF BURLINGTON, VERMONT, A CORPORATION OF VERMONT.

MOTOR FOR COIN-CONTROLLED APPARATUS.

SPECIFICATION forming part of Letters Patent No. 692,965, dated February 11, 1902.

Application filed February 21, 1901. Serial No. 48,282. (No model.)

To all whom it may concern:

Be it known that I, CHARLES ALBERT YALE, a citizen of the United States, residing at Burlington, in the county of Chittenden and State 5 of Vermont, have invented certain new and useful Improvements in Motors for Coin-Controlled Apparatus; and I do hereby declare the following to be a full, clear, and exact description of the invention, such as will enable others skilled in the art to which it appertains to 10 make and use the same.

My invention relates to motors particularly designed for use in coin-controlled apparatus, but which may be used for other purposes; 15 and the objects of the same are to simplify the construction and to render the mechanism reliable and efficient in operation and not liable to get out of order.

Another object is to simplify the winding 20 mechanism in motors of this character and to provide means whereby the motor may be wound up quickly without a lever or key.

Still another object is to provide means for giving a smooth reliable movement to the 25 weight used for operating the motor and to provide an automatic gravity clamp or clutch for the winding-cord which will permit the cord to pass freely through it in one direction and to clamp it firmly against movement in 30 the opposite direction.

These objects are attained by means of the construction illustrated in the accompanying drawings, in which—

Figure 1 is a rear elevation of the upper 35 portion of a cabinet or casing of a coin-controlled apparatus, the back board or door of the cabinet being removed to better illustrate the interior mechanism. Fig. 2 is a plan view of the motor. Fig. 3 is a vertical longitudinal section on the line xx , Fig. 2. Fig. 4 is a detail elevation of the friction-disks and the intermediate disk or wheel. Fig. 5 is a perspective view of the end of the rope-clamp. 40

Like characters of reference designate like 45 parts wherever they occur in the different views of the drawings.

Referring to Fig. 1 of the drawings, the numeral 1 designates a cabinet or casing containing the mechanism of a coin-controlled

apparatus. The numeral 2 designates the 50 motor which is made the subject of this application, and 3 is a delivery mechanism or an ejector for small packages of goods or for tickets representing goods. This delivery mechanism is made the subject of a separate 55 application for Letters Patent filed by me February 21, 1901, and bearing Serial No. 48,281. It will be understood, of course, that the motor herein described and disclosed may be used in connection with mechanism of a different character from that shown in Fig. 1.

Referring now to Figs. 2 and 3 of the drawings, which show the details of construction of the motor on a larger scale than is illustrated in Fig. 1, the numeral 4 designates a 65 winding-drum consisting of a hollow cylinder having at one end a plain disk-head 5, rigidly secured thereto in any suitable manner, and at the opposite end a ratchet-wheel 6, also firmly secured to the cylinder or drum 70 4. The axle 7 for this drum is secured rigidly at its ends in a rectangular frame 8, the axle passing freely through openings formed centrally in the disk 5 and in the ratchet-wheel 6. This construction permits the drum to 75 revolve upon the axle and does not require the ends of the axle to be journaled in the framework. The end of the drum 4 adjacent the ratchet-wheel 6 is flared outward, as at 4^a, to prevent the winding-cord riding up onto 80 the ratchet-wheel. The master-wheel 9 has a hub 10 and is also mounted to revolve freely upon the axle 7. Two oppositely-disposed pawls 11 11^a are pivoted to opposite spokes of the wheel 9, and these pawls engage the teeth 85 of the ratchet-wheel 6 and are held in operative position by the springs 12, each connected at one end to the pawl, wound once around a stud 13, projected from one of the spokes of the wheel 9, and the terminal end of the 90 spring being bent at right angles and secured in a hole in another spoke of the wheel 9, as shown in Fig. 3. The cogs on the periphery of the master-wheel 9 mesh with the teeth on a pinion 14, rigidly fixed to a shaft 15, journaled at its ends in the frame 8. Secured to the shaft 15, near the pinion 14, is a cam-disk 16, having a notch 17 and a stop 18. A face-

plate 19 is secured to the side of the cam-disk 16 by screws 20, and projecting outward from the face-plate is a stop 21, reference to which will be hereinafter made. Fixed to the shaft 15 are a pair of friction-disks 22, (see Fig. 4,) 5 adjustably spaced apart by set-screws 23, which pass through smooth holes in the outer disk and engage threads in the holes in the inner disk, thus serving to adjust the disks 10 at different distances apart for a purpose which will be hereinafter described.

Secured to the shaft 15, near its longitudinal center, is an eccentric 24, and fitted into a groove in this eccentric is a yoke 25, formed 15 on a rod 26, the terminal end of said rod being bent at right angles to connect with a portion of the delivery mechanism. A similar eccentric 27, fixed to the shaft 15, may be connected by a rod, like 26, to a register (not 20 shown) for indicating the number of times the machine has been operated or the number of coins deposited in the apparatus. Journaled to revolve freely in brackets 28, depending from the frame 8, is a shaft 29, to 25 which is fixed an insulated disk 30, said disk being beveled on opposite sides near its periphery and fitted between the friction-disks 22. A spring-brake 31, supported by an arm 32, projecting from the frame 8, bears against 30 the periphery of the disk 30 to retard its revolution and to prevent the hand-shaft 29 from such a rapid revolution that the hand or pointer could not be seen as it traverses the dial.

35 It will be understood that the motor may be used in connection with electrically-operated mechanisms, and when thus utilized a pair of electromagnets 33 may be supported upon a bracket 34, adjustably secured to the frame 8 by the screws 35, passing through slots 36 in said bracket. An armature 37 is pivoted at one end to a depending support 38 and extends over the magnets 33 in position to be within their electric field. A spring 39 is secured at one end to the armature, and its other end is attached to an adjusting-screw 40, passing through a threaded opening in an arm 41, extending out from the bracket 34. A stop-pin 42, adjustable in the arm 41, serves 45 to limit the upward throw of the armature 37 when the current through the magnets is broken, the spring 39 then lifting the armature away from the magnets. The free end of the armature 37 serves as an abutment 50 against the stop 21, and when the magnets 33 are energized the armature is attracted to them, and the abutting end thereof is moved out of the path of the stop 21, thus permitting the shaft 15 to revolve. A spring-brush 55 55 43 is secured at one end to an insulated block 44, mounted upon the arm 41. The free end of the brush 43 has a non-conducting block 45 secured to its under side, and this block bears upon the periphery of the notched disk 60 65 16. Four contact-points 46 are secured to the block 44, the free ends of said contact-points being disposed above the brush 43, near

its outer end. The brushes 46 are connected to a conductor 46^a and the spring 43 to a conductor 43^a, forming part of an electric circuit 70 in which a battery X and the electromagnet 33 are included. The spring 43 forms the armature of an electromagnet 43^b, placed in a circuit extending to contact-pieces y, adapted to be connected electrically by a coin z, inserted in the machine, the result of this action being to energize the magnet 43^b, attracting the armature 43 to it, and thus raising the block 45 out of the notch 17 and permitting the stop 18 to pass under the brush as the 80 disk 16 is revolved. When the current is broken, the spring 43 carries the block 45 into the notch 17 at the same time the end of the armature 37 comes into the path of the stop 21.

A keyhole-slot 46^a is formed in the drum 4, 85 and a rope or cord 47, Fig. 1, has a knot or stop on its end, which is inserted into the larger part of the slot 46 and moved under the smaller portion of said slot to connect the cord or rope to the drum. This cord or rope 90 passes up over pulleys 48 near the upper portion of the cabinet 1 and down to a weight 49. This weight may be of rectangular form, and a hole is formed in each side or at each 95 diagonal corner longitudinally thereof to form a guideway for two vertical rods 50, secured at their ends to the cabinet 1. By this means the weight moves smoothly up or down in performing its functions and is held in a substantially firm position for shipping. For 100 winding up the motor or for raising the weight 49 an endless rope or cord 51 is used, and this rope or cord is once passed around the drum 4, the upper strand of the cord passing up over a pulley 52, and thence laterally over 105 pulley 53 and out through the cabinet, down and around pulley 54, through an opening in the cabinet and under the pulley 55, and back to the drum.

The pulley 55 is journaled in a strong 110 spring-yoke 56, one end of which is secured to the cabinet and the free end carrying the pulley 55. The yoke 56 exerts sufficient pressure downward upon the pulley 55 to always keep the rope 51 taut. When it is desired 115 to wind up the motor, the portion of the cord 51 outside the cabinet is grasped and pulled downward, thus winding the cord 47 on the drum 4 and raising the weight 49. To prevent a backward movement of the drum after 120 each pull upon the rope 51, an automatic rope clamp or clutch 57 is employed. This clamp consists of a bracket secured to the framework of the cabinet and extending out into the path of the cord 51. The outer end of the 125 bracket is grooved, as at 58, and a clamp 59 is pivoted at 60 to the outer end of the bracket. When the cord 51 is pulled in the direction necessary to wind up the weight, it passes readily through between the outer end of the 130 bracket and the clamp. A pull in the opposite direction throws one edge of the clamp 59 against the rope and prevents the rope from a backward movement.

It will be understood that when the weight 49 descends the drum 4 revolves within the loop of rope 51, the clamp 57 holding said rope against a downward movement at that point.

5 The operation of the motor may be described as follows: It will be understood that if the different mechanisms are to be operated by electricity the proper connections will be made to start the motor when a coin has 10 been deposited in a coin-tube. When the motor is at rest, the block 45 is seated in the notch 17 in the disk 16, and the end of the armature 37 is in contact with the stop 21. When a coin, as α , is inserted in the machine, 15 an electric circuit is established through the electromagnet 43^b, the armature 43 is attracted, and block 45 is lifted out of the notch 17. At the same time the contacts 43 46 are brought together, establishing a circuit through the 20 electromagnet 33 and causing its armature 37 to be attracted out of the path of the stop 21. The weight 49 then moves downward on the 25 guide-rods 50, revolving the drum 4, and thus starting the various mechanisms which may be inclosed within the cabinet 1. When the 30 weight 49 moves downward, the rope 51, which is passed once around the drum 4, is held firmly by the clamp 57, and since the friction of the rope at the point where it surrounds the drum is not sufficient to overcome the 35 force of the weight 49 when released the drum slips within the loop of said rope. A hand or pointer may be secured to the shaft 29, and as the motor moves an initial impetus is given to said shaft, and the disk 30 is revolved between the friction-disks 22 until the hand comes to a stop. When the disk 16 has made one revolution and current has been broken, the armature 37 is raised by the spring 39 and 40 comes into contact with the stop 21, the block 45 then dropping into the notch 17 by means of the normal stress of the spring 43.

Without restricting myself to the exact construction shown, as I am aware that many 45 changes may be made in the details without departing from the spirit and scope of the invention, what I claim is—

1. A weight-operated motor comprising a winding-drum, a weight, a cord attached to the drum and weight, guide-rods upon which the weight slides, and an endless winding-cord passed around the drum and extending around pulleys to a point within easy reach of an operator for winding up the motor.

55 2. A weight-operated motor inclosed within a cabinet and comprising a winding-drum, a weight, a cord attached to the drum and weight, and an endless winding-cord passed around the drum and extending over pulleys 60 and out through the wall of the cabinet within easy access of an operator for raising the weight to wind the motor.

3. In a motor, a winding-drum, an endless winding-cord passed around the drum, and 65 an automatic clamp or clutch for said cord

which permits the cord to move freely in one direction and clamps said cord when a pull is exerted in the opposite direction.

4. In a weight-operated motor, a winding-drum, a ratchet-wheel thereon, a master-wheel carrying spring-pawls for engaging the ratchet-wheel, a weight, a cord attached to said weight and drum, guide-rods passing through the weight to steady its movements, and an endless winding-cord passed around 70 the drum and extending to a point within reach of an operator for winding up the weight.

75 5. In a weight-operated motor, a winding-drum, a weight, a cord connected to the drum and weight, guide-rods passing through the weight for steadyng its movements, an endless winding-cord passing around the drum and over pulleys to a point within easy access for winding up the weight, and an automatic 80 clamp for said winding-cord which permits the cord to move freely in one direction and clamps said cord when a pull is exerted in the opposite direction.

85 6. In a motor, a winding-drum, a cord and weight for operating the drum, a master-wheel on the drum, a pinion in mesh with said master-wheel, said pinion being fixed to a shaft carrying a notched disk, a spring-brush bearing upon the periphery of the disk, and means for throwing the brush out of the notch in the disk for permitting the motor to start and for returning the brush to the notch for stopping the motor, substantially as described.

90 100 7. In a weight-operated motor, a winding-drum, a master-wheel on the drum, a pinion in mesh with said master-wheel, a notched disk on the pinion-shaft, a spring-brush, a stop at the side of the disk, an armature normally in contact with said stop, and means for moving the armature out of the path of the stop and for returning it to its normal position.

105 110 8. In a weight-operated motor, a winding-drum, a master-wheel on the drum, a pinion in mesh with the master-wheel, an eccentric on the pinion-shaft, a yoke connected to the eccentric, a notched disk, a stop, a spring-brush, an armature, an electromagnet, and 115 means for moving the brush out of the notch in the disk, substantially as described.

9. In a weight-operated motor, a winding-drum, an endless winding-cord passing around the drum and around a system of pulleys, one 120 of said pulleys being journaled to a spring-arm for holding the cord taut, substantially as described.

In testimony whereof I affix my signature in presence of two witnesses.

CHARLES ALBERT YALE.
